UNITED STATES PATENT OFFICE.

JOHN W. LIMBERT, OF MUNCIE, INDIANA.

JAR CLOSURE.

Application filed February 26, 1921. Serial No. 442,140.

To all whom it may concern:

Be it known that I, JOHN W. LIMBERT, a citizen of the United States, residing at Muncie, in the county of Delaware and State 5 of Indiana, have invented certain new and useful Improvements in Jar Closures, of which the following is a specification.

This invention relates to improvements in closures for glass fruit jars or the like and 10 has as one of its objects to provide a simple and inexpensive clamping means for securing the closure in place upon the mouth of the jar, and which clamping means will not require to be secured upon the jar by the 15 use of a tying wire or the like.

Another object of the invention is to provide, in combination with a jar provided at the opposite sides of its mouth with trunnions, a novel clamping device for the 20 closure for the mouth which may be readily and quickly engaged with the trunnions or disengaged therefrom thus greatly facilitating the assembling of the clamping means with the jar.

25 Another object of the invention is to so form the trunnions and the element of the clamping means which is engaged therewith, as to insure of the clamping means being held against accidental disengagement from 30 the trunnions and yet not interfere with the separation or disengagement of the parts when they are intentionally manipulated for this purpose.

Another object of the invention is to so 35 form the trunnions and so construct the clamping device that when the clamping device is locked to clamp the closure to the mouth of the jar, the member of the device which is engaged with the truncheon will be 40 urged at its engaged portions inwardly toward the jar so as to provide for a snug and positive engagement between the parts.

In the accompanying drawing:

Figure 1 is a perspective view illustrating 45 the invention;

Figure 2 is a side elevation;

Figure 3 is a detail vertical sectional view through one side of the mouth closure of the jar and the clamping means for the closure;

50 Figure 4 is a perspective view of the locking bail of the clamping device.

In the drawing, the numeral 1 indicates in general a fruit or similar jar of the ordinary type provided with the usual neck 55 2 and mouth 3 which latter is closed by a cap 4 disposed thereon and resting at its

periphery upon the usual rubber ring 5 disposed to surround the mouth 3. The closure cap 4 is provided upon its upper side with the usual boss 6 having a notch 7 for the engagement of the clamping bail of the device which is to clamp the closure in place upon the mouth. For the purposes of the invention, the neck 2 of the jar is preferably thickened at diametrically opposite points, 60 as at 8, or it may be formed at such points with more or less well-defined bosses, the purpose being to reinforce the neck at these points and at the same time reinforce the trunnions previously referred to and which 65 are indicated by the numeral 9 and are formed integrally with the thickened portions 8. Each of the trunnions 9 is substantially of frusto-conical form and is integral at its minor end with the neck 2 at the respective reinforced portion 8, the outer ends 70 of the trunnions being therefore of greater diameter than the inner ends so that the circumferential surface of each trunnion provides in effect an inclined shoulder 10. In 75 order to further reinforce the neck of the jar, a reinforcing bead 11 may be formed upon the outer surface of the neck to extend circumferentially thereof between the reinforced or thickened portions 8. In the specific embodiment of the invention illustrated in the drawing, the thickened portion 8 is of circular form and concentric to the axis of the respective trunnion 9 and as this portion 80 protrudes slightly beyond the outer surface 90 of the neck 2, it will serve to suitably space the portion of the locking device which is engaged with the trunnions, from the adjacent surface of the neck and thus afford the desired clearance between the parts. 95

The clamping device embodying the invention comprises a clamping bail which is indicated in general by the numeral 12 and a locking bail which is indicated in general by the numeral 13. The bail 12 is preferably 100 formed from wire and comprises a connecting portion 14 designed to extend across the upper side of the closure cap 4 and to be engaged in the notch 7 in the boss 6. This bail further comprises depending end portions 105 15, having inwardly bent terminals 16 for pivotal engagement with the locking bail 13 as will now be explained.

The locking bail 13 is preferably formed from sheet metal and is substantially of 110 U-shape and is provided at the ends of its side portions 17 with relatively flat ears 18

each formed with an opening 19 of a diameter slightly greater than that of the trunnions 9. Being of sheet metal, the locking bail 13 is more or less resilient and it will be understood that in assembling the bail with the jar the side members 17 of the bail may be slightly spread, and the ears 18 then permitted to spring into engagement with the trunnions 9, the trunnions engaging through the openings 19, and the walls of the openings having pivotal or turning engagement with the shouleder surfaces of the respective trunnions. Beneath each ear 18 each end of the locking bail 13 is formed with a downwardly projecting ear 20 having an opening 21 in which is pivotally engaged the inwardly bent terminal 16 at the respective side of the clamping bail 12. If desired the ears 20 may be slightly deflected laterally as most clearly shown in Figures 3 and 4 of the drawings and with relation to the planes of the respective ears 18, so that the side portions 15 of the clamping bail will be adapted to suitably clear the ends of the trunnions 9 as the locking bail 13 is swung about its trunnions in clamping or unclamping the jar closure.

From the foregoing description of the invention it will be evident that the clamping device may be readily and quickly assembled with the jar and disengaged therefrom whenever required and that after application and after the closure cap 4 has been placed in position and the bail 12 engaged with the cap, the bail 13 is to be swung downwardly about the trunnions 9 as pivots and thus shift the pivot points 16 to one side of the axes of the respective trunnions 9 and bringing the intermediate portion of the locking bail 13 to position resting against the upper side of the body of the jar, in which position of the parts the closure cap 4 will be securely locked in place. As the locking bail 13 is swung downwardly to locking position, the lower sides of the walls of the openings 19 will be caused to bear upwardly against the under sides of the trunnions 9 and will ride against the inclined shoulders 10 of the said trunnions and thus be influenced to move inwardly until the ears 18 seat snugly and firmly against the outer faces of the thickened portions 8 of the neck of the jar. Thus without materially weakening the trunnions 9 or their union with the neck of the jar, I provide for an interlocking engagement of the ears 18 of the locking bail with these trunnions so as to provide against accidental disengagement of the said ears from the trunnions. In the construction illustrated,

and in practice, the axes of the trunnions 9 will be truly diametrically aligned with relation to the mouth or neck of the jar and therefore the trunnions are located more or less exactly at diametrically opposite points upon the said neck, but should it be found desirable to slightly offset these trunnions this may be done without departing from the spirit of the invention.

Having thus described the invention, what is claimed as new is:

1. In combination, a container having a mouth, a closure therefor, trunnions upon the container at opposite sides of the mouth having inclined shoulder portions, and clamping means for the closure including a bail having portions pivotally engaging the inclined portions of the trunnions.

2. In combination, a container having a mouth, a closure therefor, trunnions upon the container at opposite sides of the mouth tapered in the direction of their inner ends, and clamping means for the closure including a bail having portions pivotally engaging the tapered portions of the said trunnions.

3. In combination, a container having a mouth, a closure therefor, trunnions upon the container at opposite sides of the mouth having their lower circumferential portions inclined upwardly and inwardly in the direction of their inner ends, and clamping means for the closure including a bail having portions pivotally engaging the said inclined circumferential portions of the trunnions.

4. In combination, a container having a mouth, a closure therefor, substantially frusto-conical trunnions united at their minor ends to the outer side of the mouth, and clamping means for the closure including a bail having ears formed with openings and pivotally engaging the said trunnions.

5. In combination, a container having a mouth, a closure for the mouth, trunnions upon the container at opposite sides of the mouth having substantially conical peripheral surfaces, and clamping means for the closure comprising a locking bail having openings in its end portions receiving the trunnions with the walls of the openings engaging the said conical peripheral surfaces of the trunnions, and a clamping bail engageable with the closure and having its end portions pivotally connected with the end portions of the locking bail eccentric to the openings.

In testimony whereof I affix my signature.

JOHN W. LIMBERT. [L.S.]
